PACKAGING TRAY

Leo Cesareo, Walpole, Mass.

Application January 31, 1958, Serial No. 49,464

Term of patent 14 years

(Cl. D58—13)

Fig. 1 is a top plan view of a packaging tray showing the internal perforated bottom panel, embodying my new design,

Fig. 2 is a side elevation thereof, and

Fig. 3 is an end elevation of the tray.

Both side panels are alike and both end panels are alike, as illustrated in Figs. 2 and 3.

I claim:

The ornamental design for a packaging tray, substantially as shown and described.
